CLAIM

What is claimed is the ornamental design for a search coil for a detector, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a search coil for a detector;

FIG. 2 is a top view of the search coil for a detector;

FIG. 3 is a left side view of the search coil for a detector with portions shown in broken lines not being part of the claimed design;

FIG. 4 is a right side view of the search coil for a detector with portions shown in broken lines not being part of the claimed design;

FIG. 5 is a front view of the search coil for a detector with portions shown in broken lines not being part of the claimed design; and,

FIG. 6 is a rear view of the search coil for a detector with portions shown in broken lines not being part of the claimed design.
